EQUALIZING DEVICE FOR EXTENSION TABLES

Filed July 17, 1925

INVENTOR
E.H. COOK
BY *Mme. Lao.*

ATTORNEYS

UNITED STATES PATENT OFFICE.

EARL HERBERT COOK, OF WATERTOWN, WISCONSIN.

EQUALIZING DEVICE FOR EXTENSION TABLES.

Application filed July 17, 1925. Serial No. 44,323.

My invention relates to improvements in equalizing devices for extension tables, and it consists in the combinations, constructions, and arrangements herein described and 5 claimed.

An object of my invention is to provide an equalizing device of the character described for maintaining the extended portions of an extension table at equal distances from its 10 central support thereby properly distributing the weight of the members with respect to the central support. It should be noted of course that my improved equalizing device is not limited in its application to tables having 15 a central support, but also to tables having supports at each of the extended portions as well as central supports.

A further object of my invention is to provide an equalizing device of the character described in which particularly novel means is employed for maintaining the three co-operating members of the equalizing device against inoperative disengagement with one another.

25 A further object of my invention is to provide an equalizing device of the character described that is simple in construction, compact in form, durable, and thoroughly practical for the purpose intended.

30 Other objects and advantages will appear in the following specification, and the novel features of the invention will be particularly pointed out in the appended claim.

My invention is illustrated in the accompanying drawings, forming part of this application, in which

Figure 1 is a bottom plan view of an extension table equipped with my improved equalizing device,

40 Figure 2 is an enlarged plan view of one of the equalizing units,

Figure 3 is an enlarged sectional view along the line 3—3 of Figure 2, and

45 Figure 4 is a fragmentary perspective view of a part of the device illustrated in Figure 2.

In carrying out my invention I make use of the ordinary type of extension table having two principal parts A and B, which are intended for movement apart from one another 50 to permit the introduction at will of one or more inserts placed between the normally abutting edges 1 of the parts A and B.

My improved equalizing device forms a two-fold function of maintaining a central 55 support 2 beneath the center of gravity of the

table at all times as well as furnishing a means for supporting the parts A and B upon the central support 2.

This equalizing device consists of two units C and D disposed parallel with one another and having portions thereof secured to the member A of the table and other portions secured to the member B. The units C and D are identical in construction, one of which is shown in detail in Figure 2.

This unit consists of a central block 3 and a pair of blocks 4 and 5 disposed parallel with one another and secured against lateral movement relative to one another by the provision of metal runners 6 embedded in the blocks 3 and 5 which engage with integral portions 7 of the blocks 4 and 3 respectively, which portions 7 are greater in diameter at their outermost end so as to preclude lateral movement of the runners 6. The runners 6 are engaged primarily with the portions 7 by moving the blocks longitudinally toward one another and thus engaging the runners with the portions 7 over the ends of the portions 7. When once the blocks 3, 4 and 5 are assembled, as shown in Figure 2, it is impossible to move the blocks laterally, yet longitudinal movement of the blocks is unobstructed. The runners 6 also serve as guides for maintaining the upper surfaces of the blocks 3, 4 and 5 contiguous.

The structure indicated at 6 and 7 is well known in the extension table art. The block 3 is provided with a recessed portion 8 in the bottom wall thereof and at the mid-point of the block. A gear train consisting of three pinions 9, 10 and 11 in mesh with one another rotatably mounted upon the block 3 by means of shafts 12 is disposed between the racks 13 and 14. The pinion 9 is in mesh with the teeth of the rack 13 and the pinion 11 is in mesh with the teeth of the rack 14. The shafts 12 are secured against movement at their upper ends by engagement with a plate 12^a which is fixed to the block 3 at 12^b. The entire gear train formed of the pinions including the plate 12^a is disposed within the recessed portion 8 of the block 3.

Two lengths of angle iron 13 and 14 are secured by means of screws 15 to the lower and adjacent edges of the blocks 4 and 5 respectively. That portion of the irons 13 and 14 disposed at the adjacent side walls of the blocks 4 and 5 is embedded in the blocks by providing a suitable recess, see Figure 3, so

that the outer surface 16 of the irons 13 and 14 may lie contiguous with the outermost surface of the adjacent walls of the blocks 4 and 5.

- 5 The irons 13 and 14 are slightly more than one-half the length of the blocks 4 and 5 respectively and are disposed at opposite ends of the blocks 4 and 5 respectively. Each of the irons 13 and 14 are provided with rack teeth formed by punching angular openings 17 through the wall 16 of the irons. In Figure 4 I have shown one of the irons in perspective to more clearly show the disposition of the openings 17.
- 10 15 The units C and D are secured to the members A and B of the table by projecting screws 18 through openings 19 provided in the blocks 4 and 5 at that end opposite to the end occupied by the angle irons 13 and 14 respectively.
- 20 25 For the purpose of simplicity I shall herein-after refer to the irons 13 and 14 as racks 13 and 14.

A platform 20 having substantially the shape of the letter H is secured at 21 to the block 3 of the units C and D and the upright central support 2 is secured to the member 20.

From the foregoing description of the various parts of the device, the operation thereof 30 may be readily understood. When the parts A and B of a table equipped with my improved equalizing device are moved apart from one another as for instance the movement of the part B from the member A, as 35 shown in Figure 1, the blocks 4 and 5 which are fixed securely to the members B and A respectively must therefore move relative to one another also. This movement of the blocks 4 and 5 relatively apart from one another causes rotation of the pinions 9, 10 and 11 which are fixed except for rotative movement to the block 3. The effect of the rotative movement of the pinions caused by engagement of the toothed portion of the racks 13 and 14 therewith will be to maintain the block 3 at an equal distance from the blocks 4 and 5, thus the platform 20 bearing the central support 2 will be disposed at a mid-point between the parts A and B regardless of which of the 45 50 parts actually moves, or whether both of the parts moved with respect to the supporting

surface or floor upon which the table is disposed.

The principal feature of my invention is the peculiar structure of the racks 13 and 14 which preclude beyond all possibilities the disengagement of the pinions 9 and 11, respectively, therefrom. In the present type of equalizing devices, it is not uncommon to have the pinions temporarily disengaged from one of the racks. This will throw the entire equalizing device out of permanent adjustment and cannot function properly until the blocks are placed in their proper relative positions and the pinion reengaged with the 55 60 65 rack.

As the parts A and B are also moved apart from one another quickly and the device must necessarily stand a great deal of abuse, the racks because of the angle structure greatly 70 75 strengthen the operative parts of the units C and D and therefore are competent to stand such abuse.

It should be understood that while I have 75 shown an embodiment of my invention in the drawings employing a gear train consisting of three pinions that a gear train of three, five or seven pinions or even, if desired, may be used for the purpose of providing structure applicable to a table in which the spread is unusually great. It should also be understood that one pinion may be employed which would then engage with the racks 13 and 15 directly.

I claim:

In a device of the type described, a stationary block, a retaining member rigidly mounted upon said stationary block and spaced away therefrom, a pinion rotatably disposed between said block and said retaining member, a movable block, a gear rotatably disposed between said stationary block and said retaining member and in mesh with said pinion, and means carried by said movable block for operatively connecting said movable block with said gear, said means comprising an angle member having a plurality of spaced-apart openings providing portions arranged to mesh with said gear, said movable block being provided with an elongated groove for receiving the teeth of said gear.

EARL H. COOK.
